United States Patent Office

Des. 192,777
Patented May 8, 1962

192,777

FOOT SUPPORT OR THE LIKE

George Pahas, 1027 Cahill Road, Brooklyn, N.Y.

Filed Apr. 14, 1961, Ser. No. 64,733

Term of patent 14 years

(Cl. D83—1)

Fig. 1

Fig. 2

Fig. 3

FIG. 1 is a perspective view of a foot support or the like in wearing position, showing my new design with a foot shown in broken lines for illustrative purposes only;

FIG. 2 is a plan view thereof in open position; and

FIG. 3 is an edge view thereof.

I claim:

The ornamental design for a foot support or the like, substantially as shown and described.
